CLAIM

We claim the ornamental design for a sprinkler spike, as shown and described.

DESCRIPTION

FIG. 1 is a perspective view of a spike;

FIG. 2 is a front elevational view of the spike of FIG. 1;

FIG. 3 is a right side elevational view of the spike of FIG. 1;

FIG. 4 is a left side elevational view of the spike of FIG. 1;

FIG. 5 is a rear elevational view of the spike of FIG. 1;

FIG. 6 is a top view of the spike of FIG. 5; and,

FIG. 7 is a bottom view of the spike of FIG. 1.

The broken lines in the foregoing drawings are for the purpose of illustration and form no part of the claimed design.
